UNITED STATES PATENT OFFICE.

NELSON D. ABBEY, OF TOLEDO, OHIO, ASSIGNOR TO THE ETNA MACHINE COMPANY, OF TOLEDO, OHIO, A CORPORATION OF OHIO.

WELDER.

1,282,163.

Specification of Letters Patent. Patented Oct. 22, 1918.

Application filed May 24, 1917. Serial No. 170,628.

To all whom it may concern:

Be it known that I, NELSON D. ABBEY, a citizen of the United States of America, residing at Toledo, Lucas county, Ohio, have 5 invented new and useful Welders, of which the following is a specification.

This invention relates to guiding and directing mechanism.

This invention has utility when incorporated in holders for guiding and progressing lengths of material, for instance in seam welding apparatus as in oxy-acetylene welders.

Referring to the drawings:

15 Figure 1 is a side elevation of an embodiment of the invention in an oxy-acetylene welder for the production of tubing from rolled sheet metal stock by longitudinal seam welding;

20 Fig. 2 is a detail view showing the inner welder roll in section with features of its mounting and the guide;

Fig. 3 is a section on the line III—III, Fig. 2;

25 Fig. 4 is a plan view of the welder rolls with the delivery and receiving rolls in position relatively thereto;

30 Fig. 5 is a fragmentary side elevation of features of adjustment and mounting of the outer welder roll; and

Fig. 6 is a view of the welder rolls looking from the receiving roll side toward the delivery rolls.

35 Mounted upon the supports or legs 1 is the frame unit 2 having bearing boxes 3 for parallel shafts 4, 5, 6, 7, 8, 9, 10. This frame unit 2 positively determines the spacings between the various shafts and precludes alignment difficulties arising in machine assembly.

40 Upon the shafts 9, 10, are the delivery rolls 11, 12, in a common plane, comprising an opposing pair, the upper roller 11 having the fin 13 therein for holding the split side of the unwelded tube in position against 45 rotation so that this opening or seam may be engaged by the guide roller 14 carried by the forked stem 15 having flattened sides 16 engaged by the U-washer 17 which has openings 18 therein. In one opening 18 ex-

50 tends a pin 19 from the lower arm 20 while through the other opening 18 extends a pin 21 from the upper arm 22.

The arm 22 extends as a link to the upright shaft 23, loosely carrying the welder roll 24. This shaft 23 is vertically mounted 55 in the arm 25, swingably mounted on the pivot bearing 26, disposed in the plane of the axes of the shafts 9, 10, but transversely of said axes and in the plane of the medial tube stock carrying grooves of the opposing 60 rolls 11, 12. Also mounted on this pivot pin bearing 26 is the arm 27 carrying the upright shaft 28 on which is mounted the outer welder roll 29 as well as the arm 65 or link 20.

The pair of welder rolls 24, 29, may be adjusted in their vertical position through the action of the wheel 30 on the supplementary stem 31, serving to lift the bearing 26 and its collar 32, thereby raising the arms 70 25, 27. When the desired adjusted position is obtained, this stem 31 may be locked by the wing nut 33. This adjustment may serve to bring the center line of the groove of the rolls 24, 29, which are transverse of 75 the plane of the grooves of the rollers 11, 12, into the mid-intercepting point for accurate alinement between these delivery rolls 11, 12, and the pair of opposing receiving rolls 34, 35, that the tube pressed into 80 sealing position by the welder rolls 24, 29, may pass through these receiving rolls to the staggered straightening rolls 36, 37, 38, respectively mounted on the shafts 6, 5, 4, for delivering a completed straightened tube 85 with a continuous seam upon one side longitudinally thereof. The frame 2 is shown as having an opening therein from the top above the roll 37 (Fig. 1).

The squeezing action or approximating of 90 the welder rolls 24, 29, to each other may be adjusted by the hand wheel 39 acting on the shaft 40 having the threaded portion 41, coacting with the swivel nut 42, carried by the arm 27, the opposite end of this shaft 95 engaged by the swivel holder 43, pivotally mounted in the arm 25.

The shaft 40 is held against reciprocation relatively to the bearing 43 by the collars 44.

For alining the welder rolls 24, 29, as to 100 each other in a horizontal plane and as to the vertical plane of the terminal pair of delivery rolls and terminal pair of receiving rolls between which is this intermediate pair

of welder rolls, the bearing shaft 28 of the roll 29 is vertically adjustable through the action of the nut 45 (Fig. 5) on the threaded portion 46 of this shaft 28. The adjusted position is locked by the wing nut 47.

The arm 27 has the extension 48 as a channeled guide for the transverse guide 48' adjusted by screw 48" in which is reciprocable the upstanding arm 49 as actuated by the screw 50. This upstanding arm 49 has the pivot bearing 51 in which is mounted the rockable bracket 52, the position of which is adjusted by the screw 53 in the upstanding bracket member 49. This rockable bracket 52 has a guide section 54 carrying the screw 55 connected to reciprocate the element 56 therein. This element 56 has a transverse eye 57 through which may extend the tubular member 58, the angular position of which may be adjusted by the set screw 59.

This cylindrical or tubular member 58 has a terminal eye 60 which may be clamped by the screw 61 for holding an oxy-acetylene torch 61' in the desired position back of the guide wheel 14. Should there be any weave in the rolled sheet metal to be formed into a tube at the open side, welder rolls 24, 29, may be shifted by such traveling tube, and its mid-position holding-guide 14, to carry therewith the torch so that even these delicacies of movement may not tend to detract from a proper heating of the opposing edges so that each is sufficiently softened to be squeezed into a holding seam as it is gripped by the opposing welder rolls 24, 29, due to the driving action of the delivering rolls and the withdrawing action of the receiving rolls and straightening roll 37.

Water circulation supply is provided by the pipe 62 for effective cooling, and pet cocks 63 may deliver water into the chambers of the welder rolls 24, 29, to keep such rolls filled with water that overflow may occur through the pipes 64 into the pans 65 having waste lines 66 therefrom.

The machine may be driven from the pulley 67 on the shaft 68 acting through worms 69 and worm wheels 70 to drive the shafts 10, 8, 5, accordingly making rolls, 12, 35, 37, live rolls. The upper rolls may have their bearings adjusted toward the lower driving rolls by the hand-wheels 71 acting upon the screws 72 connected to the upper bearings 3 for the respective shafts 4, 6, 7, 9. This adjustment will take care of clearance for different gages of stock, varying diameters of the rolls, and other features of adjustment. The torch adjustment, when once determined, is automatically maintained while the nicety of the various adjustments for initially placing the welder rolls insures the production of a uniform high grade product. Whatever may be the adjustment between the oppos-

ing welder rolls, the guide wheel 14 is locked 65 for mid-travel and in the position just in advance of the torch, which relation is constantly automatically maintained.

What is claimed and it is desired to secure by Letters Patent is:

1. A machine embodying a pair of opposing delivery rolls, a pair of receiving rolls, a plurality of staggered straightening rolls, shafts for said rolls, bearings for the shafts, and a frame unit alining and spacing said 75 bearings.

2. A machine embodying two pairs of rolls in a plane, and a third relatively movable pair of rolls in an intersecting plane, the rolls of said third pair being provided 80 with a carrying support disposed in the plane of the other pairs of rolls.

3. A machine embodying three pairs of rolls, two of said pairs of rolls lying in one plane and the third pair in an intersecting 85 plane, and a pivotal mounting for the third pair of rolls.

4. A machine embodying three pairs of rolls, two of said pairs of rolls lying in one plane, the third pair of rolls being intermediate the other two pairs and lying in an intersecting plane, a pivot bearing in the plane of the two pairs of rolls, and arm means mounted on said bearing for carrying 90 the intermediate pair of rolls. 95

5. A machine embodying a pair of delivery rolls lying in a plane, a pivot bearing in the plane of said rolls, and a second pair of rolls swingably mounted on said bearing.

6. A machine embodying a first pair of 100 rolls lying in a plane, a pivot bearing in said plane, and a second pair of rolls swingably mounted on said bearing and adjustable toward and from each other.

7. A machine embodying a first pair of 105 rolls lying in a plane, a pivot bearing in said plane, a second pair of rolls swingably mounted on said bearing, and a supplemental guide between the pairs of rolls.

8. A machine embodying a first pair of 110 rolls lying in a plane, a pivot bearing in said plane, a second pair of rolls swingably mounted on said bearing, a link extending from each of said second rolls, and a guide connected to the links. 115

9. A machine embodying a first pair of rolls lying in a plane, a pivot bearing in said plane, a second pair of rolls swingably mounted on said bearing, a link extending from each of said second rolls, means for adjusting the spacing of the second pair of rolls, and a guide connected to the links, there being means coacting between the links and guide holding the guide against 120 rotation. 125

10. A machine embodying a first pair of rolls disposed in a plane, a pivot bearing in said plane, a pair of arms carried by the

bearing, a second pair of rolls carried by said arms, and means for adjusting the arms.

11. A machine embodying a first pair of rolls disposed in a plane, a pivot bearing in said plane, a pair of arms carried by the bearing, a second pair of rolls carried by said arms, and means for adjusting the bearing to shift the second pair of rolls.

10 12. A machine embodying a first pair of rolls disposed in a plane, a pivot bearing in said plane, a pair of arms carried by the bearing, a second pair of rolls carried by said arms, and means for adjusting the second pair of rolls as to each other and as to the first pair of rolls.

13. A machine embodying a pair of de-

livery rolls, a second pair of rolls disposed in a plane transversely of the plane of the delivery rolls, movable mounting means for 20 the second pair of rolls, and an adjustable arm holder carried by the mounting means.

14. A machine embodying a pair of welder rolls, swingable supporting means therefor, and an adjustable torch holding 25 bracket carried by the supporting means.

15. A machine embodying a pair of welder rolls, a swingable arm carrying each roll, there being an extension on one of said arms, and a torch carrying bracket mounted 30 on said extension.

In witness whereof I affix my signature.

NELSON D. ABBEY.
